UNITED STATES PATENT OFFICE.

HENRY W. GOODNOW, OF WORCESTER, MASSACHUSETTS, ASSIGNOR OF ONE-HALF TO
JOHN P. RYAN, OF WORCESTER, MASSACHUSETTS.

FOLDING BOX.

1,256,549.

Specification of Letters Patent. Patented Feb. 19, 1918.

Application filed March 6, 1917. Serial No. 152,603.

To all whom it may concern:

Be it known that I, HENRY W. GOODNOW, a citizen of the United States, residing at Worcester, in the county of Worcester and

5 State of Massachusetts, have invented a new and useful Folding Box, of which the following is a specification.

This invention relates to a folding box particularly adapted for attachment as a 10 match-holder to a display-card or other advertising device.

It is the object of my invention to provide a device of this type so designed that it may be folded flat for shipment or storage, and 15 that it may be placed in operative condition by the simplest manipulation.

It is a further object of my invention to provide a box of this type in which the parts will remain in operative position without 20 necessitating the use of paste or cement or other retaining devices.

An important advantage of my invention arises from this latter feature as the box may be refolded to flat or shipping condition, 25 which is often desired and not possible with a box in which the parts must be pasted or cemented together in order to remain in operative relation.

My invention further relates to arrangements and combinations of parts hereinafter described and more particularly pointed out in the appended claims.

A preferred form of my invention is shown in the drawings, in which—

35 Figure 1 is a front view of my improved folding box mounted on a display-card;

Fig. 2 is a view similar to Fig. 1, but showing the box in folded condition;

Fig. 3 is a bottom view of the device 40 shown in Fig. 1;

Fig. 4 is a similar view showing the box folded as in Fig. 2, and

Figs. 5 and 6 are vertical sectional views taken along the lines 5—5 and 6—6 in Figs. 45 1 and 2 respectively.

Referring to the drawings, I have shown my folding box as mounted upon a display-card 10 on which any desired advertising may be placed. The box itself comprises

50 two separately foldable members. One of these members consists of a front side or face 11, a back 12, and two vertical sides 13 and 14. These four parts are hingedly connected at their adjacent edges and the back

12 is commonly cemented or gummed to a 55 supporting card or other device. The front 11 may preferably receive a coating of sand to form a scratching surface.

The inner member or bottom of my improved folding box is formed of four sides 60 15, 16, 17 and 18 (Fig. 5). The length of these sides corresponds to the width of the box when unfolded, and the sides are hingedly connected at their edges similarly to the parts previously described. The side 65 17 is permanently secured to the front 11 of the box and the upper side 16 constitutes the surface upon which the matches or other articles rest.

A portion of the lower edge of the back 12 70 is cut to form lugs 19 and 20 which are left free from the display-card or support. These lugs commonly rest against the display-card when the box is folded, but when the box is unfolded the lugs may be bent outward as 75 shown in Fig. 3, in which position they form a support for the swinging side 18 of the inner member or bottom of the box.

Having described the construction of the parts of my improved folding box the relative operation thereof will be apparent. The front and side members are first moved from the position shown in Figs. 2 and 4 to that shown in Fig. 3. The lugs 19 and 20 are then bent forward if necessary and 85 the inner or bottom member is then moved downward until the outer movable edge portion of the side 18 rests upon the lugs 19 and 20. The bottom is then firmly supported and the several parts co-operate to 90 retain the box in open and usable condition. If the box is to be refolded the bottom is pressed upward against the front 11 and the outer member is then flattened as shown in Fig. 4. 95

The parts of my improved folding box are commonly formed of thin pasteboard or tag board or other similar material which may be scored to form the lines of fold. I do not limit myself, however, to the use 100 of any particular material as other kinds of flat sheet material may be readily substituted for the materials mentioned.

Having thus described my invention, it will be evident that other changes and modifications can be made therein by those skilled in the art without departing from the spirit and scope of my invention as set forth in 105

the claims, and I do not wish to be otherwise limited to the details herein disclosed, but what I do claim is—

1. A folding box having, in combination, an outer member comprising a front, back, and sides all hingedly connected at adjacent edges, a folding bottom, and means to support said bottom in operative position, said bottom being formed of four rectangular portions of sheet material hinged at the edges to form a hollow inner member having open ends and having one face secured to a face of the outer member, said bottom closing one end of said box when in operative position.
2. A folding box having, in combination, an outer member comprising a front, back and sides all hingedly connected at adjacent edges, a double folding bottom, and means to support said bottom in operative position, said means comprising integral portions of one face of said box adapted to be bent toward the interior of said box when the parts are unfolded, thereby forming a support for the bottom.
3. A folding box comprising, a foldable four-sided open-ended outer body member and a foldable four-sided open-ended inner bottom member, one side only of said bottom member being permanently secured to one

side of said body member, the lines of fold of the two members being at a right-angle to each other.

4. A folding box comprising a foldable outer or body member, a foldable inner or bottom member secured thereto, and means on said body member to support the free portion of said bottom member when the box is unfolded for use, said bottom member having four sides hingedly connected to form an open-ended hollow structure closely fitting the inside of said body member when the parts are in operative position.

5. A folding box adapted for attachment to a display-card comprising a foldable outer body member and a foldable inner bottom member, the back of said outer member being permanently secured to said display-card and having integral portions free from said card and adapted to be bent forward after the body member is unfolded, one side of said bottom member being permanently secured to the inside of the front of said body member, and said bottom member being supported by said portions when in operative position.

In testimony whereof I have hereunto affixed my signature.

HENRY W. GOODNOW.
